UNITED STATES PATENT OFFICE.

HARRY M. NAUGLE AND ARTHUR J. TOWNSEND, OF CANTON, OHIO.

EXPANDED METAL.

Original application filed April 16, 1921, Serial No. 461,806. Divided and this application filed August 22, 1922. Serial No. 583,611.

To all whom it may concern:

Be it known that we, HARRY M. NAUGLE and ARTHUR J. TOWNSEND, citizens of the United States, residing at Canton, in the county of Stark and State of Ohio, have invented a new and useful Improvement in Expanded Metal, of which the following is a specification:

The invention relates to expanded metal made of sheets, strips or the like, of the diamond mesh type in which the mesh is continuous and is composed of corrugated bonds and straight strands or bars; and the object of the improvement is to decrease the thickness of the expanded portion of the sheet and increase the truss strength of the same, which is accomplished by locating the bonds and the strands in the same plane.

The particular type of diamond mesh with which the present invention is concerned has always been produced with the alternate bonds in different planes, so that the expanded sheet has been marked by distinct series of transverse corrugations, with alternate transverse rows of bonds located in the bottom of the corrugations and the intervening transverse rows of bonds being located at the crests of the corrugations.

In the present improvement of this type of diamond mesh expanded metal, all the corrugated bonds and all the laterally inclined strands are located in the same plane, as shown in the accompanying drawings forming part hereof, in which—

Figure 1 is a plan view of the improved expanded metal, showing a series of shallow ribs located between zones of expanded mesh;

Fig. 2, a cross section of the same on line 2—2, Fig. 1; and

Fig. 3, a longitudinal section of the same on line 3—3, Fig. 1.

Similar numerals refer to like parts throughout the drawings.

The adjacent rows of bonds 4 and 4' are corrugated in reverse direction, and are so positioned that the angles of one row of the corrugations are in the same plane with the sides or edges of the other corrugations, so that the bonds as a whole are located in the same plane; and the strands 5 and 5' between the bonds are laterally inclined like the connected portion of the bonds and are formed straight without any twisting between the bonds, so as to lie in the same plane therewith.

By thus locating all the strands and connecting bonds in the same plane, the strands comprise true truss members in the lattice girder formed by the expanded mesh, which not only gives the same a minimum of thickness as a sheet but gives the same a maximum strength as a girder which is specifically desirable for use as a reinforcement for cement and concrete, and the like.

The increased girder strength of the improved expanded metal, enables the same to firmly support and sustain green cement or concrete applied to or built upon it, until it becomes set and hardened sufficiently to sustain itself; and in the improved expanded metal gives greater strength to a finished wall in which it may be used as a reinforcement.

The improved form of expanded mesh may be made in zones between unexpanded strips of a sheet, and the nonexpanded strips may be made in the form of beads or ribs as shown in the drawings; and the improved product may be made by the method and apparatus illustrated and described in our pending application for Letters Patent, filed April 16, 1921, Serial No. 461,806, of which the present application is a division. By this method and apparatus the strands are stretched or elongated so that the expanded zones are not shortened and the ribs are not contracted.

We claim:

1. Expanded sheet metal having continuous diamond meshes with reversely corrugated bonds and laterally inclined strands in the same plane.

2. Expanded sheet metal having continuous diamond meshes with corrugated bonds and laterally inclined straight strands in the same plane.

3. Metal sheets having longitudinal expanded zones and intervening nonexpanded strips, the zones having continuous diamond meshes formed therein with corrugated bonds and stretched strands, and the strips having non-contracted ribs formed therein.

4. Metal sheets having longitudinal expanded zones and intervening nonexpanded strips, the zones having continuous diamond meshes formed therein with corrugated bonds and stretched strands in the same plane, and the strips having non-contracted ribs formed therein.

HARRY M. NAUGLE.
ARTHUR J. TOWNSEND.
